(57) **CLAIM**

The ornamental design for a dual seat economy cart, as shown and described.

DESCRIPTION

FIG. 1 is an isometric view of a dual seat economy cart in a first configuration, with non-essential elements being shown in dotted lines.

FIG. 2 is a top plan view of the dual seat economy cart of FIG. 1 in the first configuration, with non-essential elements being shown in dotted lines.

FIG. 3 is a bottom view of the dual seat economy cart of FIG. 1 in the first configuration, with non-essential elements being shown in dotted lines.

FIG. 4 is a front view of the dual seat economy cart of FIG. 1 in the first configuration, with non-essential elements being shown in dotted lines.

FIG. 5 rear view of the dual seat economy cart of FIG. 1 in the first configuration, with non-essential elements being shown in dotted lines.

FIG. 6 is a left side view of the dual seat economy cart of FIG. 1 in the first configuration, with non-essential elements being shown in dotted lines.

FIG. 7 is a right side view of the dual seat economy cart of FIG. 1 in the first configuration, with non-essential elements being shown in dotted lines.

FIG. 8 is an isometric view of the dual seat economy cart of FIG. 1 in a second configuration, with non-essential elements being shown in dotted lines, with non-essential elements being shown in dotted lines.

FIG. 9 is a top plan view of the dual seat economy cart of FIG. 1 in the second configuration, with non-essential elements being shown in dotted lines.

FIG. 10 is a bottom view of the dual seat economy cart of FIG. 1 in the second configuration, with non-essential elements being shown in dotted lines.

FIG. 11 is a left side view of the dual seat economy cart of FIG. 1 in the second configuration, with non-essential elements being shown in dotted lines.

FIG. 12 is a right side view of the dual seat economy cart of FIG. 1 in the second configuration, with non-essential elements being shown in dotted lines.

FIG. 13 is a front view of the dual seat economy cart of FIG. 1 in the second configuration, with non-essential elements being shown in dotted lines; and,

FIG. 14 is a rear view of the dual seat economy cart of FIG. 1 in the second configuration, with non-essential elements being shown in dotted lines.

The elements shown in dotted lines are for illustrative purposes only and form no part of the claimed design.
